COMPOSITIONS FOR THE DYEING OF HAIR

Jacques de Brye, Casablanca, Morocco, assignor to Union Francaise Commerciale et Industrielle, Casablanca, Morocco, a corporation of Morocco

No Drawing. Application October 24, 1951,
Serial No. 252,978

Claims priority, application Morocco April 19, 1951

6 Claims. (Cl. 167—88)

This invention relates to compositions for the dyeing or tinting of hair and to methods of use thereof.

It is already known to dye hair by means of unsulphonated benzene naphthalene compounds containing, in their molecule, and in the same nucleus, three oxygen atoms arranged in such manner that the molecule contains both a phenol function and a quinone function.

Examples of such products are 2-hydroxy-1-4-naphthoquinone and the products resulting from the application of the dyeing process described in French Patent No. 826,046, which process makes it possible to obtain the transformation of trihydroxyl derivatives into quinone products on the fibre. In all such cases it is only possible to obtain shades from blonde to titian red on live hair with the aid of these products. Deeper shades can only be obtained by means of these products if they are admixed with products already known for dyeing hair, such as phenylenediamines and aminophenols, which are toxic, or by the addition of metallic salts. This latter process presents the disadvantage of not permitting subsequent capillary treatment, such as permanent waving or bleaching.

On the other hand, it is known according to J. L. Stoves and H. Burton (Journal of the Society of Dyers and Colourists, 1950-56, pages 471 to 478), that trihydroxytoluene, which is capable of acting as a reducing agent for the cystinic linkages of keratin, is capable of reacting with the keratin of the skin, thereby giving shades from brown to black (attributed to the formation of an iron complex) and with the keratin of wool at a specified pH value to give shades from a slightly reddish brown to deep brown, and also in the presence of metallic salts to give shades from medium brown to black.

I have now found a harmless composition for dyeing or tinting hair which renders it possible to obtain shades from blonde to reddish brown and bluish black, without addition of metallic salts or other products which are noxious or inconvenient for a subsequent treatment of the hair.

Accordingly, the present invention provides a composition for the treatment of hair for the purpose of dyeing or tinting which comprises a compound represented by the general formula:

wherein X represents a hydrogen or halogen atom, or an alkyl, alkoxy or hydroxy-alkyl group free from solubilising groups.

In performing the method of the invention, it is preferred to add to said composition, immediately before carrying out the dyeing of the hair, a base or a salt of a base of the group comprising ammonia and primary,

secondary or tertiary aliphatic or cycloaliphatic organic bases.

The shades are only obtained by the simultaneous action of atmospheric oxygen and the aforesaid bases.

It is therefore advantageous to modify the speed of reaction by previously incorporating in the compounds of the above general formula, reducing agents which are compatible with hair and capable of facilitating the application by retarding the development of the shade.

Reducing agents which may be used include mineral reducing agents, such as sulphites or hydrosulphites, and organic reducing agents such as sugars, and particularly the mercaptans of the general formula:

in which:

R represents a bivalent aliphatic residue, which may or may not contain an alcoholic function, and

Y represents a hydrogen atom or a carboxyl group.

The proportion of reducing agent incorporated in the composition according to the invention permits the speed of development of the shade of dyeing to be regulated, such shade being determined at the time by the nature and relative proportions of the products entering into the final dye obtained after the addition of the base or bases, or a salt of these bases, to this composition at the moment it is used.

It is assumed that the mercaptan not only performs the known function of a reducing agent which assists in the maintenance of the original qualities of the trihydroxyl substance which is used, but it also exerts a chemical or physiochemical action which facilitates the formation of the colouring on the hair; however, the invention is not to be regarded as limited by this theory.

As the invention does not include the addition of metallic salts for any of the shades obtained, it enables the superimposition of dyes and capillary treatments, such as bleaches with persalts and permanent waves to be performed without danger of changing or destroying the hair. This constitutes an essential difference both as regards the process indicated in French Patent No. 826,046 and the publication of Stoves and Burton.

The hair dyed in accordance with this novel process is characterised in all cases by a lustre not hitherto obtained by means of ordinary dyes, and as these products are not toxic, they do not necessitate any special precautions being taken, such as a test lock, which it is essential to carry out with dyes having oxidation colouring agents.

A composition in accordance with the invention is preferably provided in the form of a cream which facilitates the application to the live head of hair, by using in known manner a thickening agent and an agent having dispersive and wetting properties in order to facilitate the penetration of the dye into the hair.

Five examples showing the carrying into effect of the invention are given below, although such examples are not limitative of the scope of the said invention.

Example I

3 parts of 2-4-5-trihydroxytoluene and 0.4 part of thioglycolic acid are added to the cream obtained by emulsifying 20 parts glycol stearate in 77 parts water by means of a product having dispersive and wetting properties (such as sulphonated lauryl alcohol). At the moment of use, 10 parts of a 20% solution of ammonia are added. The mixture obtained is applied to the hair and left for about half-an-hour at 35-40°C. The hair is then rinsed, washed and dried.

The hairs are dyed black, the dye being particularly fast to washing, rubbing and light.

Example II

3 parts of 2-4-5-trihydroxytoluene and 0.4 part of thioglycerol are added to a cream obtained by emulsifying 20 parts glycerol stearate in 77 parts water by means of a product having dispersive and wetting properties (such as sulphonated lauryl alcohol). At the moment of use, 2 parts of monoethanolamine are added, the mixture obtained is applied to the hair and left for about half-an-hour at 35-40° C. The hair is rinsed, washed and dried.

The hairs are dyed a deep chestnut brown, the dye being particularly fast to washing, rubbing and light.

Example III

3 parts of 2-4-5-trihydroxytoluene and 0.4 part of thioglycollic acid are added to a cream obtained by emulsifying 20 parts of glycol stearate in 77 parts water by means of a product having dispersive and wetting properties (such as sulphonated lauryl alcohol). At the moment of use, 10 parts of triammonium phosphate are added. The mixture obtained is applied to the hair, left for about half-an-hour at 35-40° C., and the hair is rinsed, washed and dried.

The hair is dyed a deep chestnut brown with a violet glint, the dye being particularly fast to washing, rubbing and light.

Example IV

3 parts of 2-4-5-trihydroxytoluene and 0.4 part of thioglycerol are added to a cream obtained by emulsifying 20 parts of glycerol stearate in 77 parts water by means of a product having dispersing and wetting properties (such as sulphonated lauryl alcohol). At the moment of use, 3 parts of triethanolamine are added and the mixture obtained is applied to the hair. It is left for about half-an-hour at 35-40° C. and the hair is then rinsed, washed and dried.

The hair is dyed auburn, the dye being particularly fast to washing, rubbing and light.

Example V

3 parts of 2-4-5-trihydroxytoluene and 0.4 part of thioglycolic acid are added to a cream obtained by emulsifying 20 parts of glycol stearate in 77 parts water, by means of a product having dispersing and wetting properties (such as sulphonated lauryl alcohol). At the moment of use, 2.5 parts of morpholine are added. The mixture obtained is applied to the hair, and left for about half-an-hour at 35-40° C. The hair is then rinsed, washed and dried.

The hairs are dyed a shade from golden blonde to light auburn.

What I claim is:

1. A hair-dyeing composition comprising an intimate mixture of a compound free from any solubilizing group and represented by the formula

wherein X is a monovalent radical selected from the class consisting of hydrogen, halogens, alkyl, alkoxy and hydroxyalkyl groups, a mercaptan reducing agent represented by the formula

wherein R is a bivalent aliphatic residue and Y is selected from the class consisting of hydrogen and a carboxyl group, in combination with a base added immediately prior to the application of said composition to the hair, said base being selected from the class consisting of ammonia, an aliphatic amine and a cycloaliphatic amine.

2. A hair-dyeing composition as set forth in claim 1, including a thickening agent.

3. A hair-dyeing composition as set forth in claim 1, including a thickening agent and a wetting and dispersing agent.

4. A hair-dyeing composition comprising an intimate mixture of a compound free from any solubilizing group and represented by the formula

wherein X is a monovalent radical selected from the class consisting of a hydrogen, halogens, alkyl, alkoxy and hydroxyalkyl groups, a mercaptan reducing agent represented by the formula

wherein R is a bivalent aliphatic residue and Y is selected from the class consisting of hydrogen and a carboxyl group, in combination with a salt adapted to liberate a base added immediately prior to the application of said composition to the hair, said base being selected from the class consisting of ammonia, an aliphatic amine and a cycloaliphatic amine.

5. A hair-dyeing composition as set forth in claim 4, including a thickening agent.

6. A hair-dyeing composition as set forth in claim 4, including a thickening agent and a wetting and dispersing agent.
